UNITED STATES PATENT OFFICE

90,809

DESIGN FOR A LIQUID DISPENSER OR THE LIKE

Samuel J. Kaz, Chicago, Ill.

Application August 5, 1933. Serial No. 48,939

Term of patent 3½ years

To all whom it may concern:

Be it known that I, SAMUEL J. KAZ, a citizen of the United States, residing at Chicago, in the county of Cook and State of Illinois, have invented a new, original, and ornamental Design for a Liquid Dispenser or the like, of which the following is a specification, reference being had to the accompanying drawing, forming part thereof.

In the drawing:

Fig. 1 is a perspective view of my novel design for a liquid dispenser or the like.

Fig. 2 is a diagrammatic side elevation of the same upon a reduced scale.

I claim:

The ornamental design for a liquid dispenser or the like, substantially as shown.

SAMUEL J. KAZ.
